UNITED STATES PATENT OFFICE.

JOHN C. ELZY AND ERIC E. ANDERSON, OF ST. PAUL, MINNESOTA.

CABLE OR ROPE GUIDE.

No. 901,794.

Specification of Letters Patent. Patented Oct. 20, 1908.

Application filed April 10, 1908. Serial No. 426,347.

To all whom it may concern:

Be it known that we, JOHN C. ELZY and ERIC E. ANDERSON, citizens of the United States, residing at St. Paul, in the county of Ramsey and State of Minnesota, have invented certain new and useful Improvements in Cable or Rope Guides, of which the following is a specification.

Our invention relates to an improvement 10 in cable or rope guides which are adapted to be used more particularly for derricks whereby the cable or rope will be properly led to the drum of the engine.

The invention consists of certain novel 15 features of construction and combinations of parts which will be hereinafter described and pointed out in the claims.

In the accompanying drawings—Figure 1 is a view in front elevation, and Fig. 2 is a 20 view in side elevation.

The frame A of the cable or rope guide is preferably pivotally mounted on the shaft 2, at its base, which shaft passes through the base. The frame is preferably hollow 25 throughout the center and between the sides 1, 1, and preferably at the base portion sheaves 2, 2 are journaled upon the shafts 3, 3, which are mounted in the sides 1, 1 of the frame. The shafts 3, 3 are held by collars 4, 4 which are secured to one side of the frame by means of bolts 5, 5. Set screws 6, 6 extend through the collars against the shafts 3, 3 whereby they are held in position. The shafts 3, 3 are provided with 30 conduits 7, 7, which pass through the shafts for conveying oil or lubricant from the sheaves 2, 2 to oil cups 8, 8, which are connected to the conduits by means of pipes 9, 9.

The frame A projects outwardly at the 40 top and bottom as at 10, 10, and in these projecting ends rollers 11, 11 are journaled. These rollers are parallel with each other and between which the cable passes to the sheaves 2, 2, and from the sheaves the cable 45 leads to the drum upon which it is wound. By having the rollers 11, 11 extending from the ends of the frame and by the pivotal connection at the base, the guide will automatically accommodate itself according to 50 the direction in which the cable or rope is

traveling to or from the drum, and consequently friction and any undue strain are reduced to a minimum.

It is evident that more or less slight changes might be made in the form and arrangement of the several parts described without departing from the spirit and scope of our invention, and hence we do not wish to be limited to the exact construction herein set forth, but:—

Having fully described our invention, what we claim as new and desire to secure by Letters Patent is:—

1. A cable or rope guide comprising a pivotally supported frame and sheaves and 60 rollers journaled therein in pairs on axes at right angles to each other.

2. A cable or rope guide comprising a pivotally supported frame and sheaves and 70 rollers journaled therein in pairs on axes at right angles to each other, and means for lubricating the sheaves.

3. In a cable guide, the combination with a rectangular skeleton frame having orifices 75 in the top and bearings in the bottom and removable rollers let down through the orifices and stepped in the bearings in the bottom, of sheaves, removable axles therefor upon which the sheaves are loosely mounted, and collars secured to the frame and to the 80 axles.

4. In a cable guide, the combination with a rectangular skeleton frame having orifices in the top and bearings in the bottom, and removable rollers let down through the 85 orifices and stepped in the bearings in the bottom, of sheaves, removable axles therefor upon which the sheaves are loosely mounted, collars secured to the frame and to the axles, said axles having oil ducts therein, and 90 means for supplying the latter with a lubricant.

In testimony whereof we affix our signatures in presence of two witnesses.

JNO. C. ELZY.
ERIC E. ANDERSON.
